UNITED STATES PATENT OFFICE.

WILLIAM B. MURPHY, OF WEEHAWKEN, NEW JERSEY.

COLLAR BUTTON.

Application filed August 23, 1922. Serial No. 523,834.

To all whom it may concern:

Be it known that I, WILLIAM B. MURPHY, a citizen of the United States, residing at Weehawken, in the county of Hudson and State of New Jersey, have invented certain new and useful Improvements in Collar Buttons, of which the following is a specification.

This invention relates to an improved collar button.

One of the primary objects of the invention is to provide a collar button embodying means for retaining it in assembled relation with the garment to which it is applied so that not only is its loss prevented but at the same time its head is maintained in a more or less projected position with relation to the collar band so as to permit of the more ready engagement of the collar with the button.

Another object of the invention is to so construct the button that it may be readily applied to and removed from the garment and when applied will be securely retained in place.

In the accompanying drawings:

Figure 1 is a perspective view illustrating the button embodying the invention applied to the neck band of a shirt;

Fig. 2 is a detail vertical sectional view on the line 2-2 of Fig. 1;

Fig. 3 is a view partly in side elevation and partly in section illustrating a modification of the invention;

Fig. 4 is a perspective view illustrating a further modification of the invention;

Fig. 5 is a side elevation of a cuff link embodying the invention.

In that form of the invention shown in Figs. 1 and 2 of the drawings, the button is illustrated as comprising the usual back 1, head 2, and connecting shank 3, and so far as these elements are concerned they may be of any desired form and dimensions. The present invention contemplates the provision, in connection with a button of the type illustrated in said figures or a button of any other type, of a means for retaining the button properly assembled with the garment.

In the form of the invention shown in Figs. 1 and 2 of the drawings this means is indicated in general by the numeral 4 and comprises a volute wire member 5 which is anchored in any suitable manner at the terminal of its major coil, as at 6, to the inner face of the back 1 of the button, the said

element being arranged concentrically with relation to the axis of the shank 3 and having the terminal of its minor coil or convolution anchored as at 7 to the said shank 60 inwardly of the head 2. Preferably the terminal portion of the major coil or convolution of the element 5 is deflected in the direction of the back 1 of the button as indicated by the numeral 8 and it will be observed by reference to Fig. 2 of the drawings that when the head of the button is inserted through the buttonhole of the garment and the button, is rotated, the retaining element 4 will enter through the buttonhole until the 70 major coil thereof engages against one side of the neck band or other portion of the garment and the head 1 engages against the other side of said portion, the offset or deflected terminal portion 8 of the said element adapting the parts to assume this relationship. With the button so applied it will be securely retained in place and there will be no likelihood of its becoming disarranged or lost.

In that form of the invention shown in Fig. 4, the retaining element is indicated in general by the numeral 9, and the same is of the general form shown in Fig. 2 and previously described except that in this instance the element is preferably in the nature of a strip of metal coiled to volute form, as distinguished from a length of wire so formed, the convolutions of the strip being disposed substantially flatwise with relation to the 90 back of the button.

In that form of the invention shown in Fig. 3 of the drawings the retaining element is indicated by the numeral 10 and may be of wire or strip metal and is anchored at one end as at 11 to the back of the button at the extremity of its major coil, the end or extremity of the minor coil, however, indicated by the numeral 12, being left disconnected from the shank of the button but 100 more or less closely embracing the same.

Fig. 5 of the drawings illustrates the adaptation of the invention to a cuff link which is indicated in general by the numeral 13 and embodies the usual ornamental head 14, the smaller head 15, and connecting shank 16 which may be straight or curved as desired. In this form the retaining element is indicated by the numeral 17 and is preferably made from wire and of the volute form illustrated in the other figures of the drawings. In this construction the

minor coil or convolution of the retaining element may be connected to or left free from connection with the shank 16 of the link as may be found desirable.

5 Having thus described the invention, what is claimed as new is:

1. The combination with a button of the class described comprising a back, a head, and a connecting shank, of a retaining means comprising a volute member concentrically arranged about the shank of the button and having the end portion of its major coil offset in the direction of the head of the button and secured thereto at a point 10 relatively adjacent the corresponding end of the shank, the minor coil of the said member meeting the shank in juxtaposition to the head of the button.

2. The combination with a button of the class described comprising a back, a head, 15

and a connecting shank, of a retaining means comprising a volute member concentrically arranged about the shank of the button with its major coil next adjacent the head thereof and united thereto, the minor 20 coil of the member being engaged about the shank and freely slidable thereon.

3. The combination with a button of the class described comprising a back, a head, and a connecting shank, of a retaining means 25 comprising a volute member concentrically arranged about the shank of the button with its major coil next adjacent the head thereof and united thereto, the minor coil of the 30 said retaining member being united to the shank of the button inwardly of the head thereof.

In testimony whereof I affix my signature.

WILLIAM B. MURPHY. [L. s.]
